(57) **CLAIM**

We claim the ornamental design for a planter, as shown and described.

DESCRIPTION

FIG. 1 is a perspective view of a planter.

FIG. 2 is a rear plan view of the planter of FIG. 1.

FIG. 3 is a front plan view of the planter of FIG. 1.

FIG. 4 is a first side view of the planter of FIG. 1.

FIG. 5 is a second side view of the planter of FIG. 1; and, FIG. 6 is a top plan view of the planter of FIG. 1.

Portions of the planter shown in broken lines form no part of the claimed design. The broken away symbols in the drawings indicate the appearance of any portion of the article between the dash-dot break lines forms no part of the claimed design.

1 Claim, 5 Drawing Sheets
